UNITED STATES PATENT OFFICE.

S. JULIEN HELD, OF NEW YORK, N. Y.

DESIGN FOR A BOTTLE.

SPECIFICATION forming part of Design No. 25,057, dated January 21, 1896.

Application filed November 14, 1895. Serial No. 568,973. Term of patent 14 years.

To all whom it may concern:

Be it known that I, S. JULIEN HELD, a citizen of the United States, residing in the city, county, and State of New York, have invented and produced a new and original Design for Bottles, of which the following is a full, clear, and exact description.

The leading feature of my design is a bottle of substantially the configuration represented in the accompanying drawings, in which—

Figure 1 is an elevation of a bottle embodying my design, and Fig. 2 is a plan view thereof.

The bottle illustrated in the drawings consists of a base *a* and a body *b*, tapering at *c* into a neck *d*, which is crowned or surmounted by a cup *e*, whose sides are curved, the concave portion of the curve forming the interior wall of the cup. 15

What I claim is—

The design for a bottle, substantially as herein shown and described. 20

S. JULIEN HELD.
